METAL DOUBLE HUNG WINDOW

Karl F. Jorss, Washington, D. C.

Application December 6, 1935, Serial No. 53,237

12 Claims. (Cl. 189—72)

The present invention pertains to the provision of an improved metal double hung window and pertains more particularly to constructional improvements in the window frame, the sashes for said window, to the manner of weather stripping said window, to the manner of concealing the balancing or counterbalancing devices for the window sash, and other detailed constructions which will be pointed out more in detail in the following description.

One of the objects of the invention is the provision of an improved metal frame for a double hung window.

Another object of the invention is the provision of a new and improved manner of concealing and attaching the counterbalancing devices for the sliding window sashes.

Another and further object of the invention is the provision of an improved weather stripping for the window.

A still further object of the invention is the provision of an improved mechanical joint at the corners of the sash frames.

Another and still further object is the provision of an improved mechanical connection between the sash frame muntins and the members making up the sash frame itself.

Other further objects, details of mechanical improvement and improved results of a window built in accordance with the present invention will appear in more detail from the following description when read in the light of the accompanying drawings.

All of the objects and novel features of improved construction comprising the invention are for the purpose of providing an improved metal double hung window which is weather-tight, easy working, pleasing of appearance and one that is of low cost as to manufacture and cheap as to maintenance cost yet highly efficient in operation.

In the drawings:

Fig. 1 is a horizontal sectional view through a window built in accordance with the present invention.

Fig. 2 is a vertical sectional view taken on the line 2—2 of Fig. 1 looking in the direction indicated by arrow.

Fig. 3 is a detailed perspective view partly in horizontal section, of a lower corner of the improved window.

Fig. 4 is a fragmentary view in vertical section through one of the frame members of the sash.

Fig. 5 is a sectional view taken on the line 5—5

of Fig. 4 illustrating the manner of attachment of a sash muntin to the sash frame member.

Fig. 6 is a fragmentary view partly in vertical section illustrating the manner of locking the sash corner joining members in place.

Fig. 7 is a detailed perspective view of a rubbing strip.

Having reference now to the drawings, it will be seen that the frame is made up of a head member A, a sill B joined by uprights or jambs C and D. This frame is preferably composed of steel and is shaped so that the upright or jamb members provide channelways 1 and 1^a in which slide the inner and lower sash E, and with channelways 2 and 2^a in which slide the upper and outer sash F.

The frame sill is shaped to provide a sill jamb 3 and in spaced parallel relationship thereto a weathering fin 4. The frame head is shaped in a manner to provide similarly a head jamb 5 and 10 a weathering fin 6. At each of the corners of the frame there is provided an L-shaped frame securing member G made up of a pair of oppositely extending legs 7 and 8. One leg of the member is placed behind the portion 9 of the frame jamb 20 and the other and vertical leg of the member behind the vertically disposed outer edge portion 10 of the sill and a similar member, see Fig. 2 of the drawings, is similarly placed behind the frame portion 11 and behind the inner vertically disposed edge 12, see Fig. 3, of the frame sill. It is of course understood that these angle clips or securing members are welded, or otherwise suitably attached at both inner and outer corners of the frame at both its head and sill ends and 30 are the means for rigidly securing together the vertical and horizontal members making up the window frame.

The window sashes are of metallic construction and preferably aluminum. By reference to the several figures of the drawings it will be seen that the sash uprights 13 and 14 and that the sash frame sill member 15 and head member 16 are provided on their inner faces with a shallow channelway 17 adapted to receive the sash glass 45 and the putty which secures said glass in place while their opposite and outer faces or edges are provided with a channelway 18. Between the two channelways of the sash frame members the members are hollow with the result that there is 50 provided in each member a passageway or conduit 19. This passageway or conduit is utilized in the mechanical joint which I provide for securing the sash frame members together at the corners of the frame.

The particular construction of the members making up the sash frames is utilized to reduce the amount of metal used in the sash and thereby not only keep down the expense of the sash but 5 also to provide a sash which is light. The rigidity and strength of the sash frame members is assured by the inclusion of the integrally formed web 20 which constitutes one of the defining walls of the conduit 19.

10 As mentioned, I utilize this particular and peculiar construction in providing a novel and highly efficient corner joint for the sash frame members. To effect the joint I provide a metallic angle iron H, see Fig. 6, one leg 21 of which is 15 driven into the conduit 19 of the lower horizontal sash frame member 15 while the other leg 22 of the iron is driven into the conduit 18 of the vertical sash frame member 13. I say that the legs are driven in because they are of a dimension to 20 provide a driving fit with the conduits. However, to assure against any displacement of the angle irons and to assure that once the mitered corners of the frame members are properly positioned they will be maintained in proper position to one 25 another after said original fitting, I pin-prick as at 23 the upper and lower walls of the conduit to lock the sash frame members securely in proper position.

By the provision of the above described corner 30 joint for the sash frame a simple and cheap yet highly efficient joint is provided. By securing the sash frame at the corners in the manner described the cost of welding the frame at its corners or the cost incident to some other well 35 known manner of securing the frame members together is eliminated. I have found that my manner of securing the frame and its corners effects a material reduction in the cost of manufacture yet at the same time provides a securing 40 means which is highly efficient and effective in actual use.

To the end of further avoiding the necessity of 45 any form of welding I further utilize the peculiar construction of the frame members of the sash in securing the several muntins in position within the sash frame. Figures 4 and 5 of the drawings illustrate the method and construction utilized by me in this connection. At those points where a muntin is to be connected to a sash frame member oppositely disposed holes 24 and 25 are 50 provided through the walls 20 and 26 which constitute the bottom and top respectively of the conduit 18 in the frame member. The muntin J is provided at its end with a tenon 27 which is 55 inserted through the opening 25 and by the insertion of a proper tool through the opening 24 this tenon is bent or riveted down as at 28, all of which is clearly illustrated in Fig. 5 of the drawings.

60 The weather stripping for the window and particularly the jamb weather stripping is of a novel and decidedly improved construction. The weather stripping for the jambs of the window frame is designated generally at K and the particular construction and configuration of this stripping is most clearly illustrated in Figs. 1 and 3 of the drawings. The weather stripping is composed of resilient metal. The weather strip comprises a flat portion 29 which is secured as 65 at 30 by screws or the like to the flat portion 31 of the window frame jamb intermediate the sash channelways 1^a and 2^a. At each side of its flat portion 29 the strip is bent to have a portion 31 which parallels the adjacent wall of the sash 70 channelways. Beyond the portion 31 the strip is 75

curved as at 32 and then has a portion 33 which extends outwardly at an oblique angle and terminates in a convolute portion 34.

For the purpose of facilitating the application 5 of the stripping to the jamb and the positioning of the sash within the frame the weather stripping at each vertical side of the frame is in two lengths, that is to say, the strip is broken intermediate its length so that the upper and lower sections of weather stripping can be positioned in the frame independently of one another.

As is clearly evident from Fig. 2 of the drawings the coiled ends 34 of the weather strip are 15 positioned within the channels 18 provided in the edges of the vertical sash frame members, and due to the resilient nature of the strip these coils will contact the side walls which define the channelway in the sash frame members. It will be understood that as the window sashes are raised 20 and lowered they will travel along the coiled portions of the weather strip but the resilient engagement of the strips with the sash is not sufficiently great to in any manner impede such intended movement of the sash.

It is to be noted that the width of the window 25 frame channelways which receive the window sash is greater than the thickness of the sash, which assures that the sash will slide easily, and further assures that if there is any settling of 30 the building or distortion of the window frame due to that reason or any other reason there will still be no tendency for the sash to bind in the frame and thus render difficult any raising or lowering of the window sash.

It is to be noted that the ends of the weather 35 stripping are coiled in opposite directions. This is for a specific purpose. In Fig. 2 the window sash nearer the top of the drawing is the inside sash while the other is the outside sash. Any 40 wind pressure brought to bear against the outer surfaces of the window sashes has to pass the double contact of the weather strip with the walls defining the channel in the sash frame. If any 45 wind or air passes both of these contacts it is then within the coil of the weather strip and it has been found that the air pressure is largely and almost entirely dissipated within the weather strip itself due to the fact that the coil of the strip imparts a circular motion to any air which 50 may pass the strip. This dissipation of the air pressure within the strip has been found in actual practice to reduce to the minimum the chance of any outside air escaping past the window into the 55 interior of the room.

The design of the weather stripping itself is 60 such that it will yield and permit a lateral movement of the sashes which in turn will tend to overcome any possible irregularity in the manufacture of the window as well as to take care of any settlement of the masonry in the building which might tend to force or twist the window frame out of its proper or true position.

By reference to Figs. 2 and 3 of the drawings it 65 will be seen that weather stripping of the head and sill members of the upper and lower sashes is also taken care of. In the channelways of the head and sill members of the sashes there is placed a channelled non-metallic weather stripping material 35 which receives the sill and head stripping fins 4 and 6. The depth of the fins and the depth of the channelled stripping material 35 is such as to assure constant weathering even though the sashes are not moved to their fully 70 closed positions and locked. In other words, the 75

engagement between the fins and the stripping material commences prior to the complete closure of the sashes. Due to this construction weathering is also assured even though the masonry of the building may settle and tend to distort to some extent the window frame out of its proper and true position.

Weathering between the head of the lower sash and the lower end of the upper sash is provided by providing the upper sash at its lower end with an offset channelway or bracket 36 within which is positioned a strip of felt 37 or the like and providing the head of the lower sash member with a channel member 38 of the same configuration and which has its lower end 39 positioned to engage the felt strip under pressure when the sashes are in their closed positions.

To provide means for operating the lower sash the lower sash rail 15 at its inner side is provided with an integrally formed inwardly and downwardly curved portion 40 which preferably extends throughout the greater portion of the length of the member and serves as a sash operating handle.

It is always difficult to prevent infiltration of air between the opposing faces of the vertical members of the upper and lower sashes. Constructions in the past, so far as I am aware, have failed to adequately weather the window at this point. In my improved window construction it will be apparent that the upper and lower sashes are considerably separated although they lie in parallel planes. To provide against the infiltration of air at the point above referred to, I have provided an improved rubbing strip designated as an entirety at M, which is clearly illustrated in Fig. 7 of the drawings. One of these rubbing strips is provided on each jamb and by reference to Fig. 2 it will be seen that the rubbing strip extends from the point above the upper edge of the lower sash to a point below the lower edge of the upper sash when said sashes are in their closed positions. This rubbing strip comprises a short length of stainless steel metal the opposite ends 41 and 42 of which are interconnected by a bulged portion 43, which bulged portion provides a pocket for the reception of a block 44 of felt or other suitable non-metallic material. This block is of greater width than the width of the metallic strip and consequently the felt itself constitutes the weathering connection with the stiles or uprights of the upper and lower sashes, as is clearly apparent in Fig. 2 of the drawings. In this figure of the drawings it will be seen that the rubbing strip M with the felt positioned in the pocket is secured to the jamb by means of suitable screws 45 or the like which pass through the elongated openings 46 in the strip end into the jamb portion 38 intermediate the jamb sash channels. In addition to securing the rubbing strip in place these screws serve also to act as a means for securing the weather stripping K to the window frame jamb.

The sashes are provided with counterbalancing devices which are of any standard and well known type and are indicated as an entirety at P. One of these devices is of course provided in each of the window frame channelways so that there will be a counterbalancing device for each sash at each of its sides. The channelways in the window frame are unusually deep which permits these counterbalancing devices to be positioned in the channelways back of the weather stripping and also back of the sashes, with the result that the counterbalancing devices are fully

and completely concealed from view and protected from possible damage. Connection between each individual sash balancing device and the particular sash with which it functions is provided through clips Q, one end 47 of which is suitably secured to the sash adjacent its lower edge while the other end of the clip is in the form of an arm, one portion 48 of which parallels the sash frame while the other portion 49 is bent to extend into the window frame channelway 10 at a point behind both the sash and the weather stripping. This end 49 is provided with a slot 50 which receives the end 51 of the sash balancing device. To adequately lock the connection between the arm and the sash balancing device the extreme end of the arm 48 is crimped downwardly upon the end 51 of the sash balancing device, as appears at 52 in Fig. 3 of the drawings.

To permit of the construction above defined the window frame jamb channelways are of 20 greater width than the thickness of the window sash. Thus the clip arm 48 can be positioned between the sash and the side wall of a window frame channel without causing any binding upon the reciprocatory movement of the sash within 25 the jamb channel.

The particular design and construction of the window frame, the weather stripping and the manner of interconnecting the counterbalancing devices with the sash frame permits easy and quick installation of the weather stripping and easy and quick installation of the sashes themselves as well as to provide easy accessibility for the removal or installation of the concealed counterbalancing devices.

It should be of course obvious that the manner of fabricating the window frame and of fabricating the sash is such that the manufacturing cost of these members is appreciably reduced as compared to the cost of fabrication of 40 frame and sash as now commonly manufactured.

The weathering of the window is particularly effective and the convolute weather stripping has been found to be unusually effective as actual tests have indicated that due to the rotative 45 movement imparted by the strip to any air which enters it, the strip tends to so thoroughly dissipate the air pressure that good weathering of the window can be obtained even if actual contact is not maintained between the weather strip 50 and the walls of the sash channels.

Many other numerous and specific improved constructional features of the invention not only from the standpoint of manufacture but from the standpoint of installation of the window and 55 its effective operation, will be apparent to anyone skilled in the building art.

I claim:

1. A window including a channeled window frame and a sash reciprocal therein, a sash balancing device positioned beyond each end of the window sash and in the frame channel, and means extending from the sash balancing device outwardly from the frame channel and having connection with the face of said sash adjacent 65 its lower end and at a point exterior of the frame channel.

2. A window including a window frame and a sash, said frame including jambs having channels for reciprocally receiving said sash, a 70 weather stripping in said channels and having weathering engagement with said sash, a sash balancing device positioned back of the weather stripping in each of said channels, and a member extending from each balancing device outwardly 75

from the channel past the weather stripping and that portion of the sash within the channel and having attachment with the sash face at a point exterior of the frame channel.

- 5 3. In a double hung window, a window frame having jambs provided with channelways to reciprocally receive upper and lower sashes arranged in separated parallel relationship, the vertical edges of said sashes extending into said 10 channelways and themselves provided with channelways, weather stripping secured to said frame jambs at a point intermediate the jamb channelways and extending into the channelways and having weathering connection with the adjacent 15 cent sides of said channelways, the ends of said weather stripping formed in a convolute, and the convolute ends of said stripping positioned within and having weathering contact with both walls of the sash channels.
- 20 4. A construction such as defined in claim 3, wherein the convolute at one end of the weather strip is coiled towards the inner side of the window and the convolute at the other end of the weather strip is coiled towards the outer side of 25 the window.
5. A construction such as defined in claim 3 wherein counterbalancing devices for the window sash are positioned in the jamb channelways back of said weather stripping and have operative 30 connection with said window sashes at a point exterior of the jamb channelways.
6. A construction such as defined in claim 3, wherein weathering is provided between the sash and the head and sill members of the window frame and between the head and bottom frame members of the lower and upper sash respectively.
7. A window including a window frame and a sash, said frame including vertical jamb members having deep channelways for reciprocably receiving the vertical edges of said sash, the vertical end walls of said sash being provided with channelways the walls of which extend into and are loosely movable within the said jamb channels and have their edges terminating short of the backs of said jamb channels, a weather stripping in said jamb channels and provided with portions which extend into and have weathering engagement with the sash channelways, sash balancing devices in each of said frame channels and positioned intermediate the weather stripping and the backs of said channelways and connection means extending from said sash balancing devices outwardly from the frame channels and having connection with the face of the sash at a point exterior of the frame channelways, for the purpose described.
8. In a window, a window frame having vertical jambs provided with channelways adapted to reciprocably receive a window sash, the vertical end walls of said sash provided with channelways the walls of which extend into and are loosely movable within the channelways of the frame, a weather strip secured to said frame jambs at one side of its channelways and having a portion formed in a convolute which ex-

tends into and has a two-point weather engagement with the side walls of the channelway of the sash, and means to reciprocate said sash on the convolute portion of said weather strip when the sash is being opened and closed.

9. In a double hung window, a window frame having vertical jambs, each jamb provided with a pair of vertically disposed channelways adapted to reciprocably receive upper and lower sashes arranged in separated parallel relationship, 10 weather stripping secured to each of said frame jambs and having a portion which parallels one wall of each of the frame channelways and has an inwardly and forwardly extending portion which terminates in a convolute which extends 15 throughout the length of the channelway, the vertical edges of said sash provided with channelways adapted to receive and have a two-point weathering engagement with the convolutes of said weather strips, and means to slide said sash on the convolute portions of said weather strips to open and close said window.

10. In a window a window frame having vertical jambs provided with channelways adapted to reciprocably receive a window sash and a parting strip intermediate said channelways, the vertical edges of said sash provided with channelways the walls of which extend into and are loosely movable within the channelways of the frame, a weather strip for each of said frame jambs, said strips having a central portion of a U-shape in cross section and adapted to receive the parting strip and be secured thereto, the legs of said U-portions of the strips paralleling the adjacent side walls of the jamb channelways, 35 said strips beyond their U-shaped portions being bent to extend around the vertical edges of one of the walls defining the sash channelways and terminating in convolute portions which are positioned within the channelways of the sash and 40 have spring engagement with both walls of said sash channelways throughout the length of said walls, for the purpose described.

11. A structure as defined in claim 8, wherein counterbalancing devices for the window sash are positioned in the jamb channelways in the space between the backs of said weather stripping and the backs of said channelways and have operative connection with said window sash at a point exterior of the jamb channelways.

12. In a window, a window frame having vertical jambs provided with channelways adapted to reciprocably receive a window sash, the vertical end walls of said sash provided with channelways the side walls of which extend into and are loosely movable within the channelways of the frame, a weather strip on each of said frame jambs having one end in weathering connection with one wall of said frame jamb channelways and its other end extending around the edge of one wall of said sash channelway and terminating in a convolute, and the convolute end of said weather stripping being disposed within the channelways of the sash and having weathering engagement with both of the side walls thereof.

KARL F. JORSS.
